UNITED STATES PATENT OFFICE.

ISIDORE ZIPORYN, OF NEW YORK, N. Y.

WRIST FOUNTAIN-PEN.

1,322,862.

Specification of Letters Patent. Patented Nov. 25, 1919.

Application filed August 6, 1919. Serial No. 315,639.

To all whom it may concern:

Be it known that I, ISIDORE ZIPORYN, a citizen of Russia, residing in the borough of Manhattan, city, county, and State of New York, have invented a certain new and useful Wrist Fountain-Pen, of which the following is a specification.

My invention relates to fountain pens. It is a wrist fountain pen, and it is absolutely different from those used at present. Like a wrist watch, it is carried attached to the wrist, consisting of a case where ink is kept, and of an ink-supplying pipe, which is connected with the case at one end, having a gold pen-point at the other end. The pipe is made to fall between the thumb and the forefinger, and writing is performed in the usual way. It is made so as not to stain the things worn, can be used by man or woman, but it is especially handy to the woman, who otherwise has no place for the ordinary fountain pen.

In the following I describe, in connection with the accompanying drawing, a means for carrying my invention into practice.

In the drawing, Figure 1 shows the invention in use. Fig. 2 shows disconnection of parts and their places. Fig. 3 indicates how the case is attached to the wrist, and the rings through which the pipe is passed when not used.

Similar letters refer to similar parts throughout the views.

In Fig. 1, a hand is visible, on the wrist of which there is a case B, which is attached to the wrist by a strap d; on the top of the case there is a cover A, which is screwed off for the purpose of admitting ink into B, and then screwed up again; this opening can be made much larger than shown in the drawing, the top of B can be made to take the place of A, or the opening can be made on the circumference of B at any place, e is a little tube solid with B; e is an ink-supplying pipe, very delicate and ink-proof, one end being well connected with B, and the other having a gold pen-point at its extremity; the pipe near the pen admits the channeled stick

which usually comes with fountain pen-points, thus making the end of the pipe hard on one inch and a half.

The ink case is made of the material that ordinary fountain pens are made of.

The ink flows from B into e to g, when writing. The hand being much higher than the wrist, the flow of the ink is interrupted, and it becomes necessary to use out the ink present in the half of the pipe near the pen; when this is gone, the writer must simply turn slightly his or her hand sideways, toward the body, and the ink flows again into e; when this ink is gone, the same operation is repeated. B can be made to contain much more ink than ordinary fountain pens contain, for the shape and the size of the case may be varied; and in order to exhaust the ink present in the half e nearest to the pen, many sheets of paper can be covered.

The pipe e, when not used, is put around the wrist, through leather ears or rings in the strap, as r, r indicated in Fig. 3, the pen-point entering into e, which is a tube solid with B; or the pipe can be put around the circumference of the reservoir, the pen-point falling into e; or e can be made to come off B, screwed on g (Fig. 2), and then placed again on B, the latter having an opening by its side to accept it, in the form of a ring, hook or spring, as shown in Fig. 2, where the top is shown removable and independent of k, k being a ring solid with the reservoir; or the dots x indicating a spring for the same purpose.

I claim:

In a wrist fountain pen, a case for ink, means for securing the case to the wrist, a flexible pipe having a pen-point at one end being in rigid connection with the case, and writing being performed by holding the pipe between the thumb and the forefinger, the ink flowing to the pen through the pipe, the pipe when not used being adapted to be wound around the case or the wrist, and means for securing the pen-point to the case.

ISIDORE ZIPORYN,
